UNITED STATES PATENT OFFICE

FRANK L. STEWART AND MARGARET STEWART, OF FRAMINGHAM, MASSACHUSETTS

REVERSIBLE SHIRT

Application filed June 12, 1929. Serial No. 370,196.

The present invention relates to wearing apparel and more particularly to men's shirts, the invention having for its principal object to provide a garment of this character which is constructed similarly at its inner and outer side, so as to enable the shirt to be worn with either side outermost and accordingly permit the garment to be reversed when one side becomes soiled.

10 A further important object is to provide a shirt of this character equipped with an attached collar constructed in such a manner as to also permit the reversing thereof together with the shirt.

15 An additional important object is to provide a single set of buttons and button holes for the flaps of the shirt whereby the buttons may be positioned upon either side of the shirt for use in closing the opening

20 thereof. A further object embodies the construction of a garment of this character which presents a neat and attractive appearance at all times, which prolongs the life of the garment, which may be manufactured without additional cost and which at the same time is otherwise well adapted for the purpose for which the same is intended.

25 Other objects and advantages reside in the special construction, combination and arrangement of the various elements forming the invention as more fully hereinafter described and claimed, reference being had to the accompanying drawings forming part 30 hereof, wherein like numerals refer to like parts throughout, and in which:

Figure 1 is a front elevational view of the garment constructed in accordance with my invention,

40 Figure 2 is a fragmentary detail view of a portion of the flap at the opening of the shirt,

45 Figure 3 is a fragmentary sectional view taken along a line 3-3 of Figure 2,

50 Figure 4 is a detail of one of the shirt cuffs,

55 Figure 5 is a sectional view through one of the shoulder seams of the shirt taken substantially along a line 5-5 of Figure 1,

Figure 6 is a sectional view through the collar,

55 Figure 7 is a transverse sectional view through one of the cuffs, taken along a line 7-7 of Figure 4, and

Figure 8 is a sectional view through one of the flaps of the shirt illustrating the manner in which the buttons are adapted to be reversed together with the shirt.

Referring now to the drawings in detail, 60 the numeral 5 designates generally a shirt of conventional style, which includes a body 6, sleeve 7, cuff 8 and collar 9. The shirt is open at the front and each edge of the opening is provided with a reinforcing strip 65 10 which extends over both sides of the shirt material, as more clearly illustrated in Figure 3 of the drawings and with the inner edges of said reinforcing strip folded under as indicated at 11 and secured in position 70 by a row of stitching 11.

The outer edge of the reinforcing strip may also be secured to the outer edge of the garment material by a row of stitching 12. 75 The edges of the shirt opening are adapted to overlap and one edge of the opening is formed with a row of buttonholes 13 with the opposite edge of the opening provided with a row of buttons 14 disposed in proper position for insertion through said button 80 hole opening.

The edge of the material provided with the buttons 14, is recessed as shown at 15 from a point adjacent the attaching thread for the button outwardly to the edge of 85 the material so that the buttons may be forced through said recessed portion and positioned at either side of the flap of the shirt.

90 The free edges of the cuff 8, also provided with reinforcing strips 16, of a character similar to the reinforcing strips 10 and secured to the cuff material in an identical manner so that the edges of the cuff will present a similar appearance at either 95 side.

95 The outer end of the sleeve 7 is slit in the usual manner, as clearly illustrated in Figure 4 of the drawing, to permit more freedom for the insertion of the arm of the 100

wearer and the edges of said slit portion are also provided with reinforcing strips 17 of a character similar to the reinforcing strips 10 and 16 of the shirt opening and cuff respectively.

The split edges of the sleeve may also be provided with a button and button hole opening 18 and 19 respectively for closing the slit portion thereof. The edge of the material adjacent the abutment 18 is also recessed, as shown at 20 to enable the reversing of the button to a position at either side of the sleeve material.

The collar 9 is permanently attached to the panelling 21 which is customarily secured at the upper portion of the back of the shirt body 6. The panelling 21 is constructed of a double thickness of material having their lower edges turned under at opposite sides of the shirt material 6 and secured thereto by a row of stitching 22.

The collar is constructed of a band section 23 and an outer section 24, each of said sections being composed of double thicknesses of material, as clearly illustrated in Figure 6 of the drawing. In the construction of the collar the material composing the band section 23 and the outer section 24, are placed in superposed relation and one edge of all of the sections of material are secured together by a row of stitching 25.

The edges of the material of the band section are disposed outwardly with respect to the material of the outer section and are folded so that the stitching 25 is hidden and a second row of stitching 26 is then passed through the material to further secure the edges of the band section 23 and outer section 24 to each other.

The opposite edge of the band section 23 is then disposed at opposite sides of the upper edge of the panel section 21 and folded inwardly and secured thereto by a row of stitching 27.

The free edges of the outer collar section 24 are folded inwardly against each other and secured together by one or more rows of stitching 28. It will be apparent from an inspection of Figure 6 of the drawings that the outer collar section 24 may be folded into a position at either side of the band section 23 and will present the same appearance when disposed in either position.

In attaching the seam of the shirt material, the seams are disposed in overlapping relation, as clearly illustrated in Figure 5 of the drawings, both edges of the material are folded inwardly as shown at 29 and secured in position by one or more rows of stitching 30.

Accordingly when the shirt is arranged with either side outermost the edges of the seams will be entirely hidden from view.

In this manner the shirt will present a neat

and attractive appearance when the same is worn with either side outermost and accordingly by reason of the reversible characteristic of all parts of the garment, the wear to which the various parts of the garment are subjected may be equalized by periodically reversing the same.

Furthermore it will be apparent that the opposite sides of the shirt material may be printed to show different designs so that when reversed the shirt will give the appearance of constituting an entirely different garment.

It is obvious that our invention is susceptible to various changes and modifications in construction without departing from the spirit of the invention or the scope of the appended claims, and we accordingly claim all such forms of the device to which we are entitled.

Having thus described our invention, what we claim as new is:

A reversible shirt including a body portion, sleeves, cuffs and a collar permanently attached to each other and having the edges of the connecting seam folded under to present a finished appearance at each side of the material, reinforcing strips for the flap of the shirt opening and for said cuff also having the edges of said strips folded under similar to the folded edges of the seams, one of said flaps having a row of button-holes the other of the flaps having a row of buttons, said last named flap having recesses extending inwardly from and entirely through its edge and terminating adjacent the buttons and through which recesses the buttons may be inserted for positioning upon the surface of the shirt when in either an obverse or reverse position, the edges of the recesses cooperating with the backs of the buttons, to maintain the latter upon the surface of the shirt when in either position.

In testimony whereof we affix our signatures.

MARGARET STEWART.
FRANK L. STEWART.
